UNITED STATES PATENT OFFICE.

EDWARD J. KNAPP, OF SYRACUSE, NEW YORK.

SANCTUARY-LAMP.

1,200,121.

Specification of Letters Patent.

Patented Oct. 3, 1916.

Application filed April 27, 1916. Serial No. 93,897.

To all whom it may concern:

Be it known that I, EDWARD J. KNAPP, a citizen of the United States, residing at Syracuse, in the county of Onondaga and 5 State of New York, have invented certain new and useful Improvements in Sanctuary-Lamps, of which the following is a specification.

This invention relates to improvements in 10 sanctuary lamps, and has for its object to provide a novel, simple and convenient fixture designed particularly for use in churches and other religious places where lamps of the class are used.

15 A further object is to provide a sanctuary lamp wherein a candle composed of suitable slow burning wax is employed instead of the various oils which have heretofore served as the illuminant or fuel for such lamps.

20 A further object is to provide novel and simple means for conserving the fuel of the lamp so as to prolong the lighting interval as well as to obviate the waste usually attendant 25 the burning of wax candles.

A further object is to provide novel means for the self-adjustment of certain parts of the lamp and for the proper ventilation of the same.

30 I attain these objects by the means set forth in the detailed description which follows, and by reference to the accompanying drawing in which—

Figure 1 is a side elevation, of one form 35 of my improved lamp. Fig. 2 is a top plan view of the same, the ornamental screen being omitted. Fig. 3 is a horizontal section, taken on line 3—3 of Fig. 1. Fig. 4 is a top plan view of the base of the lamp. Fig. 5 is 40 a central vertical section, taken on line 5—5 of Fig. 2. Fig. 6 is an elevational view of the lamp, in which the base of Fig. 1 is omitted and means for suspending the lamp are substituted. Fig. 7 is a central vertical section; showing the weight in engagement with the candle support as during the 45 final consumption of the candle. Fig. 8 is a horizontal section, taken on line 8—8, of Fig. 7.

50 In the drawing, 2 represents the main base, preferably hollow and made of sheet metal, but a satisfactory base-part may be made of any other suitable material. The lower portion of the base consists of a flange 55 3, while the upper portion 4 thereof is substantially cylindrical and hollow. Within

the portion 4 is an annular ledge 5, which is perforated at 5' for the admission of air. 6 represents a pan or cup of peculiar shape which is disposed loosely in the base 2, 60 and has a shoulder 7 which rests upon the ledge 5. The interior of the pan 6 is provided with a ledge 8 corresponding to the part 5.

9 represents a disk-shaped candle support, 65 having a shallow recess 9' in its top side, to receive the bottom of the candle 10. The support 9 is connected to a similar concentrically arranged part or base 11, by a neck or column 12. The base 11 is larger in 70 diameter than the part 9, and has an annular recess 11', the said recess having perforations 13, at intervals around the neck 12. As the candle 10 melts away by the heat of the burning wick 10', some of the unconsumed wax may flow over the support 9, 75 into the recess 11' of the base 11, and thence drip or gravitate through the perforations 13, and is collected in the pan 6.

13' represents an annular flange depending from the bottom of the base 11 for preventing the molten wax flowing through the holes 13 from reaching, as by capillary attraction, the joint between said base and the pan 6. By this arrangement, any residue 80 of the wax, after the candle has been used up, is taken care of entirely within the base 2 of the lamp, and there is no danger of any of the wax escaping from the lamp. To the disk or plate 11, is suitably secured 85 two or more guide-rods 15, which extend vertically parallel to each other to a considerable height above the candle support 9. When a new candle is placed in the upright position on the support 9, between the 90 rods 15, a circular or ringlike weight or follower 16, having holes or ways 17 for receiving the guide-rods 15, is disposed directly over and concentric to the top end of the candle 10. The weight 16 is in the form 95 of a heavy ring, preferably made out of metal, as considerable weight is required to effect a tight seal between the inner sloping surface 16' of the ring and the upper end or head of the candle to prevent the escape 100 of the molten wax. The opening in the top of the ring 16, is smaller than the diameter of the candle, and the said opening is provided with an inturned-flange 18, which 105 preferably rests upon the tapering or peaked top-end of the candle. Below the flange 18 the weight is counterbored for

providing an annular chamber or space 19 surrounding the candle. The object of the chamber 19 is to provide for the free circulation of air, adjacent the point of contact 5 between the ring 16 and the candle, to prevent the undue heating of the weight and consequently the more rapid melting of the wax of the candle. By thus cooling the weight, the melting or wasting of the outer 10 circumferential portion of the candle is retarded or prevented to such extent that the weight will ride firmly and evenly upon the candle, thereby conserving the fuel and prolonging the light for a period of a week or 15 ten days, without requiring the renewal of the candle. The wax of the candle, as it becomes melted by the heat of the burning wick, is retained in the cuplike opening 18' between the flange 18 and the top of the 20 weight. To further aid in retaining the melted wax at the point where the wick is burning, as well as to protect or shield the flame of the wick from drafts, I insert a transparent chimney 20, (preferably red 25 glass) in the opening 18' in the top of the follower 16. The lower end of the chimney 20 preferably fits snugly into the opening 18' of the follower and also rests upon the upper side of flange 18. In practice, after 30 the wick has burned for a short time, the melted wax wells up in the chimney 20 slightly above the level of the top of the weight 16, as indicated by the dotted line 21, in Fig. 5. The wick projects slightly above 35 this melted wax, and burns for a long time, both the wick and the wax comprising materials that consume slowly. As the candle melts and wastes away under the heat of the burning wick, the weight 16 and the chimney 20 gravitate with the candle, the former being guided by the rods 15, (see dotted lines in Fig. 5) which hold the said parts in true upright position, until all of the solid wax of the candle is melted. By that 40 time the weight, or an internal annular shoulder 22 thereof, comes to rest upon the peripheral flange or edge 9" of the support 9, and forms therewith a chamber 23 (see Fig. 7). As a rule, most of the melted wax 45 which remains after the weight contacts with the support 9 is confined in chamber 23, (see Fig. 7) and the light will continue to burn as long as any of the wick and wax-oil remains. Outside of the weight 16, the 50 candle and its support 9—11, and the cup 6, is disposed a relatively large transparent cylindrical globe or part 24 (preferably red glass), the lower end of which snugly fits into the portion 4 of the base 2, the said 55 end preferably resting upon the ledge 5 of said base. The globe 24 is preferably spaced sufficiently from all of the parts above the base to provide a roomy air chamber for supplying the requisite amount of 60 oxygen for the proper burning of the can-

dle after the same has melted away to a point below the top of the globe 24. The arrows in Fig. 5 indicate the course of the air from the time it enters the perforations 5' in the ledge 5, until it finally escapes 70 through the open top of the said globe. By referring to Fig. 5, it will be seen that the top portion of the cup 6 is smaller in diameter than the bottom of the globe 24, which allows the free passage of the air from the 75 holes 5' into the globe.

25 represents a wire-cage screen, the lower end of which is disposed in and supported by the bell-top of the globe 24, for excluding the larger insects, such as beetles 80 and moths, which are usually attracted by lights of the kind.

To make-up my improved sanctuary lamp ready for operation, the pan 6 is inserted in the base 2; the candle support 9—11 is then 85 disposed in the pan 6; the candle 10 is next placed upon the support 9, and the weight 16 is mounted upon the guide-rods 15 and brought into contact with the top of the candle where it remains. The chimney 20 is 90 next inserted in the opening 18', followed by the insertion of the globe 24 in the base 4, and lastly the cage 25 is placed in position. The lamp is then ready to be lighted. In practice, the candles 10 are made of a 95 slow burning wax and are usually provided in sizes which will burn continuously for 7 to 10 days without renewal. Figs. 1 and 5 show the lamp completely assembled ready to start a lighting period, and Fig. 7 shows 100 the condition of the working parts of the lamp during the final stages of the said period.

Fig. 6 illustrates a modification of the sanctuary lamp in which 27 represents a 105 hollow base arranged to receive the waste wax cup and the candle supports, and also the lower end of the globe 24', the said base having an annular flange 27'. The globe 24' is suspended in a collar or ring 28, 110 which is supported some distance above the base 27 by means of rods 29, the latter being suitably secured to the flange 27', and also to the ring 28. The upper ends of the rods 29 are formed into hooks 30 to which the 115 lower ends of chains 31 are attached. The upper ends of the said chains are attached to an ornamental part 32, which is provided with a hook or loop 33, by which the whole fixture is suspended, as from a ceiling. The 120 working parts of the hanging lamp of Fig. 6 and also the operation thereof, are substantially the same as shown for the standing lamp, illustrated by Figs. 1 to 5 inclusive.

It is obvious that some change or modification may be made in the parts of the device, within the scope defined by the appended claims, without departing from the spirit of the invention.

Having thus described my invention, what I claim as new and desire to secure by Letters Patent is—

1. A sanctuary lamp including a wax candle, a support for the candle, a weight mounted on top of the candle, said weight having a recessed opening in its top, and a chimney inserted in said opening and coöperating with said weight for retaining the melted wax while the candle is burning.

2. In a sanctuary lamp, the combination of a candle, a support for the candle, said support having a perforated base, a pan to receive the molten wax dripping from said perforated base, a main base for supporting said pan, and a globe inserted in the main base and inclosing the candle, its support, and said pan.

3. In a sanctuary lamp, the combination 20 with a candle, a hollow base, and a pan telescoping said base, of a support for the candle supported within said pan, a chambered ring mounted on the top of the candle, the tip of the candle and its wick projecting above said ring, and a globe inserted in said base and surrounding the candle, the support, and said ring.

4. In a sanctuary lamp, the combination 25 with a candle, and a support for the candle, of a pan in which said support is disposed, a base for receiving said pan, a chambered ring mounted upon the top end of the can-

dle, guide-rods carried by the support and piercing said ring, a chimney disposed in the opening in said ring adjacent to the top 35 end of the candle, and a globe inserted in the base and surrounding the candle and the said ring.

5. In a sanctuary lamp, the combination 40 of a candle, a support for the candle, a pan for receiving said support, a main base for receiving said pan, said base having a plurality of perforations for admitting air, a globe inserted in the main base and inclosing the candle and its support and conducting the air received from the main base toward the top of the candle, and an annular weight mounted on the top of the candle, the said weight having a chamber to receive the air supplied by the globe for cooling said 50 weight.

6. In a candle-lamp, the combination of 55 the candle, a recessed support for the candle, the said support having a perforated base, guide-rods supported by said base, a chambered ring-shaped weight pierced by said guide-rods and telescoping the top end of the candle, means for air-cooling the said weight, and a chimney inserted in the open top of the weight adapted to be partially 60 filled with melted wax during the burning of the candle.

In testimony whereof I affix my signature.
EDWARD J. KNAPP.
